MILL ROLL STAND

Louis W. Roselius, Lake Success, N. Y., assignor
to S & S Corrugated Paper Machinery Co., Inc.,
Brooklyn, N. Y., a corporation of New York

Application April 14, 1947, Serial No. 741,217

2 Claims. (Cl. 242—58)

1

My present invention relates to mill roll stands, and more particularly to apparatus for rotatably supporting a mill roll of heavy kraft paper intended to be utilized in various corrugating operations to form either single-face, double-face or double-double corrugated board.

Heretofore in the construction and operation of mill roll stands, it has been thought necessary to support the mill roll at its core either by a shaft pushed through the core or by core studs 10 entering partly into the core.

An important object of my invention is the provision of a mill roll stand which need not necessarily support the mill roll at any predetermined level and in which the support of the mill roll does not take place at the core.

Another object of my invention is the provision of simplified roller means for supporting a mill roll, said roller means supporting the mill roll peripherally and permitting it to unwind under the pull exerted on the sheet by the corrugating apparatus in which the kraft paper is to be used.

Mill rolls of this type weigh as much as a ton or even more and are thus difficult to handle. In constructions where the mill roll must be supported at the core, the frame-work supporting the mill roll must be cross-braced and sufficiently strong to take the load. This makes it necessary to provide a relatively tall structure, the bracing and strengthening of which requires additional expense.

By supporting the mill roll peripherally by a pair of rollers or sets of rollers adjacent the floor, the necessity for a complex interbraced structure is eliminated.

I further contemplate that my novel device be so arranged that as the diameter of the mill roll decreases on unrolling the kraft paper, the rollers which support the same peripherally are automatically brought closer together in order continuously to apply full support to the roll irrespective of its diameter.

The foregoing and many other objects of my invention will become apparent from the following description and drawings in which

Figure 1 is a side view of my novel mill roll apparatus.

Figure 2 is a view corresponding to that of Figure 1 showing various positions of my novel mill roll supporting apparatus.

2

Figures 3 and 4 are schematic views illustrating the automatic operation of my novel mill roll stand for adjusting the supporting rolls as the diameter of mill roll decreases.

5 Figure 5 is a plan view of the mill roll stand with the mill roll removed therefrom.

Figure 6 is a cross-sectional view taken on line 6—6 of Figure 5 looking in the direction of the arrows.

15 Figure 7 is a schematic view of the electrical circuit required for automatic operation of my novel mill roll stand.

Referring now to Figures 1, 2, 5 and 6, my novel mill roll stand 10 is shown supporting the mill roll 11 which rests on rolls 12 carried by shaft 13 supported in appropriate bearings in the brackets 15—15, which brackets may be cross-braced in any suitable manner as by the cross-rods 17. The opposite support for the mill roll 11 comprises the rollers 20 on shaft 21 rotatably mounted on the movable carriage formed by brackets 23, 23 and 24.

20 25 Each of the brackets 23, 23 and 24 is provided with wheels 26, 26 rolling on tracks 27, 27. The outer brackets 23, 23 of the adjustable rolls 20 on shaft 21 are each provided with a collar 30 which receives the end 31 of screw shaft 32. Washers 34 and 35 on the end 31 of screw shaft 32 permit the screw shaft 32 to rotate with respect to the collar 30 but do not permit any longitudinal movement with respect thereto. Screw shaft 32 passes through bearing 40 and 40a mounted on bracket 41. This structure is duplicated for each side.

30 35 40 Means are provided as hereinafter described for causing the screw shaft 32 to move longitudinally in bearings 40 and 40a to move the brackets 23 to result in movement of brackets 23 and hence in corresponding movement of roll 20 from the position shown by the solid lines of Figure 3 to the position shown by the solid lines of Figure 4 and also to the various positions shown in Figure 2.

45 50 This is accomplished by motor 50 mounted on bracket 51 and the driving worm 52 which meshes with spiral gear 53 on shaft 54. Shaft 54 is carried in bearings 55, 55 on bracket 51 and in bearings 56, 56 on brackets 41 and terminates at each end in the bevel gears 58, 58 which mesh with the bevel gear 59, 59 on each of the screws 32.

The bevel gears 59 as shown particularly in the cross-sectional view of Figure 6 have an internally threaded nut extension 62 which meshes with the screw shaft. The bevel gears 59 are fixed against the longitudinal movement by sleeve 63 placed between the bevel gear and bearing 40a and also by the ledge 64 which bears against the outer surface of bearing 49 on the opposite side of the bevel gear 59.

Each bevel gear 59 is freely rotatable in the bearing 40. Thus it will be seen that rotation of bevel gears 59 result in corresponding rotation of their nut extension 62 to rotate the screws 32 to move the brackets 23 to adjust the length of the paper sheet.

In practice two such mill roll stands are used simultaneously as shown in Figures 1 and 2. The paper 70 from the left-hand mill roll stand is carried under and around guide rolls 71 mounted on shaft 72 and over guide rolls 73 mounted on shaft 74. Shafts 72 and 74 are rotatably carried between side frame members 75. Before the paper 70 from the left-hand mill roll stand is used up, the paper 80 from the right-hand mill roll stand is carried around the opposite side of its guide roll 71a on its shaft 72a and then secured to the surface of the paper 70 above the guide roll 71. Before the paper 80 is used up, the leading edge of paper 70 is carried around its guide roll 71 and adhesively secured to the paper 80 above the guide roll 71, as indicated in Figure 2.

The brackets 23, 23 are provided with extensions 90, 91, one of which carries a light source 92 and the other of which carries a photoelectric cell 93, the light source 92 being focused on the photoelectric cell 93. As the mill roll 11 decreases in diameter, as shown at Figure 3, it drops down to intercept the light from light source 92 so that it does not strike the photoelectric cell 93.

Appropriate relays are then operated in response to the cutting off of light from the photoelectric cell 93 to operate the motor to drive the brackets 23 to the left with respect to Figures 1 to 4 in order to raise the mill roll. When the brackets 23 have been moved sufficiently to the left, then the mill roll is raised up once more, as shown in Figure 4.

Again as the mill roll 11 drops down owing to decrease in diameter, the motor is once more energized to drive the rolls in until the position shown in Figure 2 is reached, where the mill roll has been reduced to its minimum diameter and is finally being used up. One of the screws 32 may be provided with a switch operating arm 95 to operate the micro-switch 96 to open the circuit to the motor and thus disconnect the motor when the supporting rolls for the mill roll have been driven sufficiently and thus to prevent over-driving by the motor.

The operation is shown very schematically in the view of Figure 7 in which current from the power source 100 is connected to operate the device when the double pole switch 101 is closed. Current then flows over conductor 102 through the limit switch 96 to motor 50, then through conductor 103 and relay armature 104 to conductor 105 and back to the power source 100. Conductor 103 is also connected to one terminal of the winding 107 of the relay; the other terminal is connected through conductor 108 and amplifier 109 and conductors 110, 111 to the photoelectric cell 93 so that the winding is controlled thereby.

The return circuit is through conductor 112

and conductors 103 to motor 50 and conductor 102. The light source 92 is energized from conductors 115 and 116 connected respectively to conductors 102 and 105.

Thus it will be seen that in operation it is necessary only to pull out the brackets 23 sufficiently to support the full size mill roll. In order to facilitate this operation, the worm gear 52 may be provided with a crank socket 130 to receive a crank handle so that the bracket may be pulled out sufficiently or the motor 50 may be a reversing motor with appropriate circuit connections or an appropriate reversing gear connection may be applied to the worm gear 52 or the spiral gear 53.

The mill roll 11 is then rolled in on the dolly 140 between the rolls 12 and 20. Push button switch 145 which short-circuits the relay armature 104 is then closed to energize the motor 50 to drive the rolls 20 to the left with respect to Figure 1. These rolls are moved in until the roll 11 is lifted off the dolly 140, then the switch button 145 is opened and the dolly 140 is removed.

On unwinding of the paper and resultant decrease in diameter of the mill roll, the light impinging on the photoelectric cell is intercepted thus re-energizing the motor to move the rolls 20 in once more to lift the mill roll up so as to clear the light source and thus ensure that the mill roll is sufficiently high off the floor. The rolls 12 and 20 will obviously be spaced sufficiently to provide a proper bearing for the mill roll; however, should there be any danger of the mill roll falling off the stand, this may be obviated by appropriate side roll elements including idler rolls carried by the brackets 23 and 15 and spring biased against the sides of the mill roll thereby tending to hold the mill roll properly in place.

In the foregoing, I have described my invention solely in connection with preferred illustrative embodiments thereof. Since many variations and modifications of my invention should now be obvious to those skilled in the art, I prefer to be bound not by the specific disclosures herein contained but only by the appended claims.

I claim:

1. A mill roll stand for supporting a roll of paper while the same is being unwound; said stand comprising a pair of parallel freely rotatable spaced idling rollers for carrying the mill roll; said rollers being initially spaced apart less than the diameter of the mill roll; means for moving one of said rollers toward the other as the diameter of the mill roll decreases during unwinding; said last mentioned means comprising a moving mount for said first mentioned roller; a motor and a connection between said motor and said mount for moving said mount toward and away from said other roller; and means responsive to the decrease in size of the mill roll for controlling the operation of said motor to move said mount toward the other roller as the diameter of the mill roll decreases.

2. A mill roll stand for supporting a roll of paper while the same is being unwound; said stand comprising a pair of parallel freely rotatable spaced idling rollers for carrying the mill roll; said rollers being initially spaced apart less than the diameter of the mill roll; means for moving one of said rollers toward the other as the diameter of the mill roll decreases during unwinding; said last mentioned means comprising a moving mount for said first mentioned roller; a motor and a connection between said motor and said mount for moving said mount toward and

away from said other roller; and means for automatically controlling the operation of said motor to move said mount toward the other roller as the diameter of the mill roll decreases; said automatic means including a light source on one side of said mill roll stand, a photo-sensitive device on the opposite side, the light beam of the light source impinging on the photo-sensitive device; said light beam traversing the mill roll stand between the rollers and below the level thereof; said light beam being intercepted when the diameter of the mill roll is decreased sufficiently to cause it to lower itself between the rollers, and a connection between the photo-sensitive device and the motor.
